VOLTAGE REGULATOR

Filed Sept. 7, 1951

UNITED STATES PATENT OFFICE

2,607,912

VOLTAGE REGULATOR

Adolph O. Bunblasky, New Canaan, and Allen K. Brown, Stamford, Conn., assignors to Sorensen & Company, Inc., Stamford, Conn., a corporation of Connecticut

Application September 7, 1951, Serial No. 245,538

13 Claims. (Cl. 323—45)

1

This invention relates to new and useful improvements in voltage regulators and has particular relation to a regulator for controlling the voltage from an alternating current power supply so that said voltage remains virtually constant over a relatively wide range of predetermined voltages.

In general, the present regulator includes a bridge type network having a diode vacuum tube forming one of the arms of the bridge. The filament of the diode is connected across the output of the voltage regulator whereby the temperature of the filament changes in response to changes in the output voltage. This temperature change then results in a change in the plate resistance of the diode and a subsequent unbalance of the bridge circuit. The output of the bridge is then fed through a filter network in order to reduce any component ripple voltage and is used to control the output from the first stage of a cascaded amplifier. The output from the first stage is fed through a second filter network into the second stage.

The output from the cascaded amplifier is then fed through another filter circuit which nullifies any tendency for the circuit to hunt and is then applied to the control grid of another vacuum tube. The plate current of this latter tube is fed through the direct current winding of a saturable core reactor in order to control the impedance of the alternating current winding. As this winding is in series with a lead common to the input circuit and output circuit of the regulator, the voltage is varied in accordance with the impedance of the alternating current winding. Thus, the output of the regulator can be controlled to maintain a substantially constant voltage even though the loads may change.

It is an object of the present invention to provide a highly stable electronic voltage regulator of the character generally described above, which is adapted to control the output voltages approximately $\pm .01\%$ against variations due to changes in the line voltage or the load.

It is another object to provide a highly stable voltage regulator which can maintain a substantially constant voltage output in the range of $\pm .01\%$ with power factors in the range of approximately .9 capacitive and .7 inductive.

Another object is to provide a highly stable voltage regulator, whereby should the emission from any of the vacuum tubes included in the circuit fail, the output voltage would tend to drop rather than rise thereby protecting any

2

equipment fed from the output from being damaged by excessive voltage.

Another object is to provide a highly stable voltage regulator meeting the above objects and also providing a virtually distortionless alternating current output.

Still another object is to provide a highly stable voltage regulator adapted to start even under large loads.

10 The above and other objects of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

20 In the drawing the figure represents a schematic diagram of one embodiment of the invention.

Referring in detail to the drawing, an alternating current input is applied to a pair of input terminals 10 and 11 and is thence fed through 25 a pair of contacts 12 and 13 of "on-off" switch 14. The side of the line connected to the terminal 10 through the switch contact 12 is connected directly to a tap 15 on an auto-transformer 16 through a lead 12a. The other side of 30 the line, i. e., that connected to the terminal 11 through the switch contact 13, is fed by a connection 17 through the alternating current windings 18 and 19 of a saturable core reactor 20, which also has a direct current winding 21, 35 to a terminal 22 of the auto-transformer 16. Thus, the alternating current windings 18 and 19 are in series with the connection 17 forming part of a feed line to the auto-transformer 16.

The alternating current output is developed 40 across the outer ends of the auto-transformer 16 and appears across the terminal 22 and a terminal 23. The terminal 23 is carried by a connection 24 through a thermal-overload switch 25 to an output terminal 26. Another output terminal 27 is connected directly to the connection 17 by means of a lead 28.

In order to filter out any third harmonic distortion which might be otherwise present at the output, a network comprising a pair of capacitors 50 29 and 30 and an inductance 32 is provided. The capacitors 29 and 30 are connected in parallel and this combination is then connected in series with the inductance 32 across the output lines formed by the connections 17 and 24. In order 55 to filter out any fifth harmonic distortion, a

filter comprising a series combination of a capacitance 33 and an inductance 34 is also connected across the connections 24 and 17. An inductance 35 is placed across the terminals 26 and 27 in order to provide an inductive load so as to make the regulator capable of handling loads with a capacitive power factor.

A transformer 36 is associated with the control circuit presently to be described in detail. The primary 37 of the transformer 36 is connected directly across the output terminals 26 and 27. An end terminal 38 is connected through a fuse 39 to the output terminal 26. Another end terminal 40 is directly connected by a lead comprising the sections 41, 42, 43, 44 and 45 to the other output terminal 27.

A secondary 46 of the transformer 36 is connected directly across the plates 47 and 48 of a rectifier tube 49. Another secondary 51 is connected across the filament 52 of the rectifier tube 49 to provide heating current therefor. A direct current voltage is thus developed across a terminal 53 associated with the filament 52 and a center-tap 54 on the secondary 46. This voltage has, of course, a decided ripple which is effectively reduced by a capacitor 55 and a resistance 56 connected across the terminal 53 and the center-tap 54. Resistance 56 also serves as a voltage divider to provide voltage of a proper value for the screen grid 57 of a vacuum tube 58.

The vacuum tube 58 is associated with the control circuit hereinafter fully described. Briefly, however, the plate current from the vacuum tube 58 is fed through the direct current winding 21 of the saturable core reactor 20 to control the impedance of its alternating current windings 18 and 19.

Plate 59 of the vacuum tube 58 is connected through a load resistance 60 to the terminal 53 of the rectifier 49. The direct current winding 21 is connected in parallel with the load resistance 60. The negative terminal of the rectified supply, as represented by the terminal 54, is connected directly to a cathode 62 of the vacuum tube 58. A bleeder resistance 61 is provided between the plate 59 and the screen grid 57.

The filament 63 of the vacuum tube 58 is supplied from a secondary 64 (which cooperates with the primary 37 to provide a filament transformer portion of the transformer 36) and a secondary winding 65 of a booster transformer 66, both secondaries 64 and 65 being connected in series. A pilot light 67 is connected across the secondary 64. The primary winding 68 of the booster transformer 66 is connected between the terminals 23 and 15 of the auto-transformer 16. The secondary winding 65 in series with the secondary winding 64 acts as a booster which enables the regulator to start even under large loads.

By way of example, assuming a load of 1000 volt-amperes and a voltage input to the regulator of only 95 volts, if the unit is then turned on by closing the "on-off" switch 14, the voltage across the secondary 64 of the transformer 36 may be so low as to prevent the filament 63 from heating. By providing the secondary winding 65 of the booster transformer 66, the voltage across the filaments will be sufficient to allow the vacuum tube 58 to heat up and thereby make the control circuit operative. Once the control circuit operates, the normal filament voltage is developed across the filament 63.

The principle of booster transformer 66 is that the difference between the input and the output voltage is impressed on the primary of this trans-

former. When the control circuit is not operating, this difference is relatively large and thus applies a correspondingly large boost to filament 63. Once the control circuit operates, the difference becomes small and a very negligible, if any, boost is applied to filament 63.

A Wheatstone type bridge circuit comprising arms formed by resistances 10, 71, and 72 and a diode vacuum tube 73 is provided in order to detect changes in the voltage across the output terminals 26 and 27. The diode vacuum tube 73 is preferably a special diode, as fully described in a copending application of Helterline et al. entitled Filament Failure Device for Electronic Tubes filed April 1, 1949, under Serial Number 84,806. This diode has the characteristic that should the tube fail for any reason, the filament is shorted to the plate. This is illustrated schematically in the figure by an arm 74 connected to a plate 75 of the diode 73, said connection being within the envelope of said diode. Upon failure of the tube, due to its filament 76 burning out, arm 74 comes in contact with the filament 76 of the diode 73, thereby shorting said plate 75 to the filament 76.

Although a conventional diode may be used in place of the special diode described, it is preferable to use such a special diode as a safety precaution. By way of example, upon failure of the special diode 73, the short circuiting of the plate and filament results in a decrease in the output voltage across the terminals 26 and 27. This is of importance if equipment sensitive to high voltages is being supplied by the regulated output. If a conventional diode were used, the output voltage would tend to rise with possible subsequent damage to the equipment being supplied.

One side of the filament 76 is connected by a lead 77 through a pair of serially connected dropping resistances 78 and 79, thence by a lead 81 to a movable pole 82 of a single pole double throw switch 83. A contact 84 of the switch 83 is connected to a variable resistance 85. The other contact 86 is connected to a second variable resistance 87 and the two ends of the variable resistances 85 and 87 are connected to a lead 88. Thus, when the movable pole 82 is against contact 84, leads 81 and 88 are connected together through the variable resistance 85. In a similar manner, when the movable pole 82 is against contact 86, the leads 81 and 88 are connected together through the variable resistance 87. By means of the switch 83 and the variable resistances 85 and 87, the filament current may be varied in order to adapt the circuit for operation over a wide range of desired output voltages.

Lead 88 is connected to the lead 41 and thence to the terminal 40 associated with the primary 37 of the transformer 36. The other side of the filament 76 is connected through a lead 90 thence by a lead 91 to the terminal 38 of the primary winding 37. As the voltage across the terminals 38 and 40 is the same as that across the outputs 26 and 27, it is evident that the filament 76 is likewise across the outputs and its temperature and hence emission will vary with changes in the output voltage.

A transformer 92 has its primary winding 93 also connected across the regulated output voltage. One end terminal 94 is connected by a lead 95 to the lead 91 and thence to the terminal 38. Another end terminal 96 is connected by a lead 97, thence by the lead 43 to a terminal 98 of the tube socket for the diode 73, thence from another terminal 99 and the lead 44 to the lead 45 and

the output terminal 27. The terminal 94 is connected through the tube socket of the diode 73 so that in the event the diode 73 is removed, one side of the line to the primary 63 of the transformer 92 and the primary 31 of the transformer 36 is automatically opened.

This results in the power supply including the diode 49 being deenergized, thus removing plate voltage from the vacuum tube 58. Therefore, the current through the direct current winding 21 of the saturable core reactor 20 is reduced to zero and the impedance of the alternating current portions 18 and 19 increases to reduce the voltage across the output terminals 26 and 27. As mentioned in connection with the description of the diode 73, this is an important safety feature for protecting any sensitive equipment fed from the output terminals 26 and 27.

A secondary winding 102 of the transformer 92 provides a voltage supply for the bridge circuit. The alternating current developed across the secondary 102 is rectified by a suitable rectifier 103 which may be of the selenium, copper oxide or, in fact, of any convenient type. One side of the rectifier 103 is connected to a terminal 104 of the secondary 102 and the other side is connected through a resistance 105 and a resistance 106 to an input terminal 107 of the bridge circuit. The other terminal 108 of the secondary winding 102 is connected directly to another input terminal 109 of the bridge circuit. A capacitor 110 is connected from the terminal 108 to the junction of the resistances 105 and 106.

The capacitance, in conjunction with the resistance 105, serves as a filter network to smooth out the rectifier ripple and the resistance 106 serves as part of a voltage divider to predetermine the voltage across the bridge input terminals 107 and 109. Neon tubes 111, 112, 113 and 114 are connected across the input terminals 107 and 109 to further stabilize the voltage applied to the bridge. As the primary 93 of the transformer 92 is connected across the regulated output terminals 26 and 27, the output of the rectifier 103 is quite stable but, by providing the neon tubes, still further voltage stability is achieved. A constant input voltage to the bridge circuit insures that the output of the bridge will vary only in accordance with changes in the impedance of the vacuum tube 73.

An increase in the voltage will cause the filament 76 of the diode 73 to increase in temperature with a resulting increase in emission. This causes the impedance of the diode 73 to decrease and a resulting unbalance in the bridge. This unbalance further results in a change in the voltage appearing across a pair of bridge output terminals 115 and 116 causing the terminal 115 to become more negative with respect to the terminal 116.

The output voltage developed across the output terminals 115 and 116 of the bridge circuit is applied to a filter network 117 connected between a control grid 118 and a cathode 119 of a dual vacuum tube 120. The filter network 117 comprises two serially connected capacitors 123 and 124 connected in parallel with a resistance 125. The resistance 125 is connected between the bridge output terminal 115 and the control grid 118. A resistance 126 is connected between the junction of the serially connected capacitors 123 and 124 and the cathode 119 of the vacuum tube 120.

The filter network 117 is adapted to reject or greatly attenuate any 120 cycle ripple appearing

on the direct current voltage developed across the output of the bridge. The 120 cycle ripple is introduced in the circuit by virtue of the full wave power supply comprising the transformer 36 and the dual-triode vacuum tube 49. An additional 120 cycle ripple is also introduced into the circuit due to the thermal effect of the diode filament. By attenuating this ripple, the voltage appearing across the control grid 118 and the cathode 119 is almost a pure direct current voltage except for a small 60 cycle ripple introduced by the power supply to the bridge circuit, and the half of the vacuum tube comprising the grid 118, the cathode 119 and a plate 127 can act as a direct current amplifier.

The plate supply voltage for the plate 127 is developed from a secondary winding 128 of the transformer 92. One terminal of the secondary 128 is connected through a conventional rectifier element 129 thence through a resistance 130 to the plate 127. The other terminal of the secondary winding 128 is connected through a filter capacitor 131 and thence to the plate 127. A pair of serially connected resistances 132 and 133 are connected as a bleeder across the capacitor 131.

A second filter network 135, similar in arrangement to the filter network 117, is connected between a control grid 136 and a cathode 137 of the other half of the dual-triode vacuum tube 120. The network 135 comprises two serially connected capacitors 138 and 139 connected in parallel with a resistance 141. The resistance 141 is connected between the cathode 119 of the first half of the dual-triode and the control grid 136 of the second half. Thus, the output from the first half of the dual-triode 120 is taken from the cathode 119. A resistance 142 is connected between the junction of the capacitors 138 and 139 and the cathode 137 of vacuum tube 120.

The function of filter 135 differs from that of the filter 117 in that filter 135 is adapted to reject or greatly attenuate 60 cycle ripple rather than 120 cycle ripple. This ripple originates from the power supply providing voltage to the bridge input terminals 107 and 109. This 60 cycle ripple is amplified by the first half of the dual-triode vacuum tube 120 so as to be at a higher level than the direct current component. It therefore must be attenuated before it is applied to the control grid 136 of the second half of the tube in order that the second half of the tube may also act as a direct current amplifier.

A plate 143 of the second half of the dual-triode is connected to a source of potential by a lead 144 to the bleeder resistance 56 connected across the output of the power supply formed by the transformer 36 and the duo-diode 49. The filaments 145 of the vacuum tube 120 are supplied directly from a secondary 146 of the transformer 92.

The end of the resistance 141 connected to the cathode 119 is also connected through a resistance 147 to the secondary winding 128 of the transformer 92. The end of the resistance 142 which is connected to the cathode 137 is connected also to the junction between the bleeder resistances 132 and 133. The potential of the cathode 137 is then at a higher positive potential than the control grid 136 and the tube is biased.

As it is desirable to furnish a negative bias voltage for a control grid 134 of the vacuum tube 58, a power supply to provide said biasing voltage is provided. Said power supply comprises a secondary winding 158 of the transformer 92, one

terminal of said secondary being connected to one terminal of a rectifier 159 similar to the rectifier 103. The other side of the rectifier 159 is connected through a resistance 160 and a resistance 161 and thence by a lead 162 and the lead 148 to the control grid 134 of the vacuum tube 58. The other terminal of the secondary 158 is connected by a lead 163 and the lead 155 to the cathode 62 of the vacuum tube 58. A capacitor 164 is connected between said last mentioned terminal and the junction of the resistances 160 and 161 to cooperate with the resistance 160 as a filter network to smooth out the rectifier ripple.

It is thus seen that the input to the first half of the vacuum tube 120 is applied between the grid 118 and the cathode 119. The output from the cathode 119 is then applied to the filter 135 to eliminate 60 cycle ripple and thence impressed between the control grid 136 and the cathode 137. This causes the voltage at the cathode 137 to change resulting in a change in the bias on the grid 134 of the vacuum tube 58. By way of example, assume the output voltage tends to rise. This causes the filament 76 of diode 73 to increase in temperature with a resulting increase in emission causing a decrease in the impedance of the diode and a resulting unbalance in the bridge. This unbalance is manifested as a decrease in the potential of the terminal 115 with respect to the terminal 116.

As terminal 115 is connected to the grid 118 of vacuum tube 120 and the terminal 116 is connected to the cathode, the grid 118 is made more negative with respect to the cathode causing the current in the tube to decrease. As the cathode follows the grid, its potential likewise drops. Now, as the cathode 119 is also connected through the resistance 141 to the control grid 136 of the other half of the tube 120, the potential of the grid 136 will also drop as will the potential of the cathode 137. As the cathode 137 is connected by a lead 148 through a resistance 149 to the control grid 134 of the vacuum tube 58, the potential of the control grid 134 will also decrease.

Therefore, the plate current through the tube 58 is decreased with a resultant decrease in the current through the direct current winding 21 of the saturable core reactor 20. This causes an increase in the impedance in the alternating current coils 18 and 19 and a concomitant decrease in the magnitude of the alternating current voltage output. A decrease in the output voltage would cause the same cycle of events but in the reverse direction.

A filter network 151 similar in arrangement to the filter networks 117 and 135 is connected between the grid 134 and the cathode 62 of the vacuum tube 58. The network 151 comprises two serially connected capacitors 152 and 153 connected in parallel with the resistance 149. A resistance 154 is connected with the junction of the capacitors 152 and 153 and the cathode 62. This latter connection is made by a lead 155. Thus, the output voltage from the cathode 137 of the tube 120 is applied through the filter 151 to the grid-cathode circuit of the vacuum tube 58. This filter prevents hunting which occurs when the control circuit overshoots. For example, if the output voltage rises, the control circuit may over-correct and this cycle will continue at a comparatively low frequency, the value of which will depend upon the time constants in the various resistance capacitor combinations in the control circuit. A frequency of approximately 2.5 cycles is typical and hence if a filter capable of rejecting this frequency is placed across the grid-

cathode circuit of the vacuum tube, hunting will not take place.

Another anti-hunting feature is provided by connecting a pair of capacitors 156 and 157 across the primary 37 of the transformer 36. The cathode 62 of the vacuum tube 58 is connected to the junction of the capacitors 156 and 157. When the circuit tends to overshoot and the grid 134 is being actuated in one direction, an alternating current voltage is applied to the cathode 62 so as to counteract the overshoot of the grid voltage.

Having thus set forth the nature of our invention, what we claim is:

1. A highly accurate electronic voltage regulator adapted to regulate the magnitude of an alternating current voltage between predetermined limits, said regulator including an input circuit, transformer means having a first portion associated with said input circuit, an output circuit connected with a second portion of said transformer means, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a direct current amplifier, filter means associated with said direct current amplifier, means for applying the output of said bridge circuit through said filter means to said direct current amplifier whereby said filter means is adapted to reject unwanted alternating current ripple which may be present in the output from said bridge circuit, vacuum tube means, means for applying the output from said direct current amplifier to said vacuum tube means to control the plate current thereof, and means for applying said plate current to the direct current portion of said saturable core reactor to control the impedance of said alternating current portion and to thereby maintain the voltage of said output circuit within said predetermined limits.

2. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof, the filament of said diode being connected across said output circuit whereby a variation in the output voltage varies the temperature of said filament to thereby unbalance said bridge, a direct current amplifier, filter means associated with said direct current amplifier, means for applying the output of said bridge circuit through said filter means to said direct current amplifier whereby said filter means is adapted to reject unwanted alternating current ripple which may be present in the output from said bridge circuit, vacuum tube means, means for applying the output from said direct

current amplifier to said vacuum tube means to control the plate current thereof, and means for applying said plate current to the direct current portion of said saturable core reactor to control the impedance of said alternating current portion and to thereby maintain the voltage of said output circuit within said predetermined limits.

3. A highly accurate electronic voltage regulator adapted to regulate the magnitude of an alternating current voltage between predetermined limits, said regulator including an input circuit, transformer means having a first portion associated with said input circuit, an output circuit connected with a second portion of said transformer means, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a direct current amplifier, filter means associated with said direct current amplifier, means for applying the output of said bridge circuit through said filter means to said direct current amplifier whereby said filter means is adapted to reject unwanted alternating current ripple which may be present in the output from said bridge circuit, vacuum tube means having at least a plate, a control grid and a cathode, an anti-hunting means, said means comprising a filter network between said control grid and said cathode, said filter network being adapted to reject the frequency at which said regulator would tend to hunt, means for applying the output from said direct current amplifier through said anti-hunting means to the control grid of said vacuum tube means to control the plate current thereof, and means for applying said plate current to the direct current portion of said saturable core reactor to control the impedance of said alternating current portion and to thereby maintain the voltage of said output circuit within said predetermined limits.

4. A highly accurate electronic voltage regulator adapted to regulate the magnitude of an alternating current voltage between predetermined limits, said regulator including an input circuit, transformer means having a first portion associated with said input circuit, an output circuit connected with a second portion of said transformer means, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter means connected between the grid and cathode of said first vacuum tube means, a second filter means connected between the grid and cathode of said second vacuum tube means, each of said filter means being adapted to attenu-

ate separately alternating current ripple components superimposed on the output from said bridge circuit, means for taking the output from the cathode of said first vacuum tube means and applying it through said second filter means to the control grid of said second vacuum tube means, a third vacuum tube means having at least a plate, a cathode and a control grid, an anti-hunting means, said means comprising a filter network between said last mentioned control grid and cathode, said filter network being adapted to reject the frequency at which said regulator would tend to hunt, means for taking the output from the cathode of said second vacuum tube means through said anti-hunting means to the control grid of said third vacuum tube means to control the plate current thereof, and means for applying said plate current to the direct current portion of said saturable core reactor to control the impedance of said alternating current portions and to thereby maintain the voltage of said output circuit within said predetermined limits.

5. A highly accurate electronic voltage regulator adapted to regulate the magnitude of an alternating current voltage between predetermined limits, said regulator including an input circuit, transformer means having a first portion associated with said input circuit, an output circuit connected with a second portion of said transformer means, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter means connected between the grid and cathode of said first vacuum tube means, a second filter means connected between the grid and cathode of said second vacuum tube means, each of said filter means being adapted to attenuate separately alternating current ripple components superimposed on the output from said bridge circuit, means for taking the output from the cathode of said first vacuum tube means and applying it through said second filter means to the control grid of said second vacuum tube means, a third vacuum tube means having at least a plate, a cathode and a control grid, a first anti-hunting means, said means comprising a filter network between said last mentioned control grid and cathode, said filter network being adapted to reject the frequency at which said regulator would tend to hunt, means for taking the output from the cathode of said second vacuum tube means through said first anti-hunting means to the control grid of said third vacuum tube means to control the plate current thereof, a second anti-hunting means, said means comprising a plurality of serially connected capacitors connected across said output circuit, a connection from the junction of two of said serially connected capacitors to the cathode of said third vacuum tube means, and means for applying the plate current of said third vacuum tube means through the direct current portion of said satu-

rable core reactor to control the impedance of said alternating current portion to thereby maintain the voltage of said output circuit within said predetermined limits.

6. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a saturable core reactor having an alternating current portion and a direct current portion, means for altering the voltage across said output circuit by varying the impedance of said alternating current portion, a bridge circuit having a special diode forming one of the arms thereof, said special diode having an arm adapted to short the diode plate to its filament in the event said filament burns out, the filament of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter means connected between the grid and cathode of said first vacuum tube means, a second filter means connected between the grid and cathode of said second vacuum tube means, each of said filter means being adapted to attenuate separately alternating current ripple components superimposed on the output from said bridge circuit, means for taking the output from the cathode of said first vacuum tube means and applying it through said second filter means to the control grid of said second vacuum tube means, a third vacuum tube means having at least a plate, a cathode and a control grid, an anti-hunting means, said means comprising a filter network between said last mentioned control grid and cathode, said filter network being adapted to reject the frequency at which said regulator would tend to hunt, means for taking the output from the cathode of said second vacuum tube means through said anti-hunting means to the control grid of said third vacuum tube means to control the plate current thereof, a first transformer forming a portion of a power supply adapted to supply direct current voltage to said third vacuum tube means, a second transformer forming a portion of a power supply adapted to supply direct current voltage to said bridge circuit, one side of the primary winding of each of said transformers being connected to one lead of said output circuit, the other side of each of said primaries being connected to one of a pair of vacant terminals on the usual tube socket associated with said special diode, the other of said pair of terminals being connected to the other lead of said output circuit, a strap across the vacant terminals on said special diode which engages with the aforementioned pair of vacant terminals on said usual tube socket when said diode is in said socket whereby under such condition the primaries of said first and second transformers are connected across said output circuit but in the event said diode is removed said transformers are disconnected from said output circuit to prevent the voltage across said output from exceeding the predetermined voltage and thereby preventing damage to apparatus supplied from said voltage regulator, and

means for applying the plate current of said third vacuum tube means through the direct current portion of said saturable core reactor to control the impedance of said alternating current portion to thereby maintain the voltage of said output circuit within said predetermined limits.

7. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a saturable core reactor having an alternating current portion and a direct current portion, means for altering the voltage across said output circuit by varying the impedance of said alternating current portion, a bridge circuit having a diode vacuum tube forming one of the arms thereof, the filament of said diode being connected across said output circuit whereby a variation in the output voltage varies the temperature of said filament to thereby unbalance said bridge, a direct current amplifier, filter means associated with said direct current amplifier, means for applying the output of said bridge circuit through said filter means to said direct current amplifier whereby said filter means is adapted to reject unwanted alternating current ripple which may be present in the output from said bridge circuit, vacuum tube means having at least a plate, a control grid, a cathode and a filament, an anti-hunting means, said means comprising a filter network between said control grid and said cathode, said filter network being adapted to reject the frequency at which said regulator would tend to hunt, means for applying the output from said direct current amplifier through said anti-hunting means to the control grid of said vacuum tube means to control the plate current thereof, a first filament transformer for supplying current to said filament, the primary of said first filament transformer being connected across said output circuit, a booster filament transformer for supplying current to said filament, the primary of said booster transformer being connected across a lead of said input circuit and a lead of said output circuit, the secondary of said booster transformer being connected in series with the secondary of said first filament transformer, the sum of the voltages across said secondaries being applied to said filament whereby under heavy initial loads a voltage appears across the primary of said booster transformer to thereby supply additional voltage to said filament enabling said filament to heat sufficiently to allow said regulator to function and upon functioning no voltage appears across said booster transformer, and means for applying the plate current of said vacuum tube means to the direct current portion of said saturable core reactor to control the impedance of said alternating current portion and to thereby maintain the voltage of said output circuit within said predetermined limits.

8. A highly accurate electronic voltage regulator adapted to regulate the magnitude of an alternating current voltage between predetermined limits, said regulator including an input circuit, transformer means having a first portion associated with said input circuit, an output circuit connected with a second portion of said transformer means, a saturable core reactor having an alternating current portion and a direct

current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter means connected between the grid and cathode of said first vacuum tube means, a second filter means connected between the grid and cathode of said second vacuum tube means, each of said filter means being adapted to attenuate separately alternating current ripple components superimposed on the output from said bridge circuit, means for taking the output from the cathode of said first vacuum tube means and applying it through said second filter means to the control grid of said second vacuum tube means, a third vacuum tube means having at least a plate, a control grid, a cathode and a filament, an anti-hunting means, said means comprising a filter network between said control grid and said cathode, said filter network being adapted to reject the frequency at which said regulator would tend to hunt, means for applying the output from said direct current amplifier through said anti-hunting means to the control grid of said vacuum tube means to control the plate current thereof, a first filament transformer for supplying current to said filament the primary of said first filament transformer being connected across said output circuit, a booster filament transformer for supplying current to said filament, the primary of said booster transformer being connected across a lead of said input circuit and a lead of said output circuit, the secondary of said booster transformer being connected in series with the secondary of said first filament transformer, the sum of the voltages across said secondaries being applied to said filament whereby under heavy initial loads a voltage appears across the primary of said booster transformer to thereby supply additional voltage to said filament enabling said filament to heat sufficiently to allow said regulator to function and upon functioning no voltage appears across said booster transformer, and means for applying the plate current of said vacuum tube means to the direct current portion of said saturable core reactor to control the impedance of said alternating current portion and to thereby maintain the voltage of said output circuit within said predetermined limits.

9. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a saturable core reactor having an alternating current portion and a direct current portion, means for altering the voltage across said output circuit by varying the impedance of said alternating current portion, a bridge circuit having a special diode forming one of the arms thereof, said special diode having an arm adapted to short the diode plate to its filament in the event said filament burns out, the filament

of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter means connected between the grid and cathode of said first vacuum tube means, a second filter means connected between the grid and cathode of said second vacuum tube means, each of said filter means being adapted to attenuate separately alternating current ripple components superimposed on the output from said bridge circuit, means for taking the output from the cathode of said first vacuum tube means and applying it through said second filter means to the control grid of said second vacuum tube means, a third vacuum tube means having at least a plate, a cathode and a control grid, an anti-hunting means, said means comprising a filter network between said control grid and cathode, said filter network being adapted to reject the frequency at which said regulator would tend to hunt, means for taking the output from the cathode of said second vacuum tube means through said anti-hunting means to the control grid of said third vacuum tube means to control the plate current thereof, a first transformer forming a portion of a power supply adapted to supply direct current voltage to said third vacuum tube means, a second transformer forming a portion of a power supply adapted to supply direct current voltage to said bridge circuit, one side of the primary winding of each of said transformers being connected to one lead of said output circuit, the other side of each of said primaries being connected to one of a pair of vacant terminals on the usual tube socket associated with said special diode, the other of said pair of terminals being connected to the other lead of said output circuit, a strap across the vacant terminals on said special diode which engages with the aforementioned pair of vacant terminals on said usual tube socket when said diode is in said socket whereby under such condition the primaries of said first and second transformers are connected across said output circuit but in the event said diode is removed said transformers are disconnected from said output circuit to prevent the voltage across said output from exceeding the predetermined voltage and thereby preventing damage to apparatus supplied from said voltage regulator, a rectifier associated with a secondary of said second transformer to supply direct current to said bridge, a plurality of gas-filled electronic tubes connected across the output of said rectifier to regulate the voltage applied to said bridge, filter means connected across said output circuit to remove third and fifth harmonic distortion and means for applying the plate current of said third vacuum tube means through the direct current portion of said saturable core reactor to control the impedance of said alternating current portion to thereby maintain the voltage of said output circuit within said predetermined limits.

10. A highly accurate electronic voltage regulator adapted to regulate the magnitude of an alternating current voltage between predetermined limits, said regulator including an input circuit having the primary of an auto-transformer connected thereto, an output circuit as-

sociated with the secondary of said auto-transformer, a saturable core reactor having an alternating current portion and a direct current portion, means for altering the voltage across said output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a double stage direct current amplifier having a first vacuum tube means and a second vacuum tube means, each of said vacuum tube means having at least a plate, a cathode and a control grid, a first filter network connected between the grid and cathode of said first vacuum tube means, said filter network comprising a pair of serially connected capacitors connected in parallel with a first resistance, one end of said first resistance being connected to the grid of said first vacuum tube means, the other end of said first resistance being connected to an output terminal of said bridge, a second resistance having one end connected to the junction of said serially connected capacitors, the other end being connected to the cathode of said first vacuum tube means, said filter network being adapted to reject a component alternating current ripple appearing on the output voltage from said bridge, a second filter network connected between the control grid and cathode of said second vacuum tube means, said second filter also comprising a pair of serially connected capacitors connected in parallel with a first resistance, one end of said last mentioned first resistance being connected to the control grid of said second vacuum tube means, the other end being connected to the cathode of said first vacuum tube means, a second resistance having one end connected to the junction of the serially connected capacitors of said second filter network, the other end being connected to the cathode of said second vacuum tube means, said second filter network being adapted to reject a component alternating current ripple appearing on the output voltage from the cathode of said first vacuum tube means, a third vacuum tube means having at least a plate, a cathode and a control grid, an anti-hunting means, said means comprising a filter network between said last mentioned control grid and cathode, said filter network being adapted to reject the frequency at which said regulator would tend to hunt, means for taking the output from the cathode of said second vacuum tube means through said anti-hunting means to the control grid of said third vacuum tube means to control the plate current thereof, and means for applying said plate current to the direct current portion of said saturable core reactor to control the impedance of said alternating current portion and to thereby maintain the voltage of said output circuit within said predetermined limits.

11. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a lead of said input circuit being common with a lead of said output circuit, a saturable core reactor having an alternating current portion and a direct current portion, said alternat-

ing current portion being connected in series with the lead common to said input circuit and said output circuit, an inductance and a capacitance in series therewith, said combination being connected across said output circuit to remove fifth harmonic distortion from said output, a second inductance and a capacitance in series therewith, said second combination likewise being connected across said output circuit to remove third harmonic distortion from said output, a third inductance connected across said output circuit to inductively load said output circuit, a bridge circuit having a diode vacuum tube forming one of the arms thereof the filament of said diode being connected across said output whereby a variation in the output voltage varies the temperature of said filament to thereby unbalance said bridge, a double stage direct current amplifier having a first vacuum tube means and a second vacuum tube means each of said vacuum tube means having at least a plate, a cathode and a control grid, a first filter network connected between the grid and cathode of said first vacuum tube means, said filter network comprising a pair of serially connected capacitors connected in parallel with a first resistance, one end of said first resistance being connected to the grid of said first vacuum tube means, the other end of said first resistance being connected to an output terminal of said bridge, a second resistance having one end connected to the junction of said serially connected capacitors, the other end being connected to the cathode of said first vacuum tube means, said filter network being adapted to reject a component alternating current ripple appearing on the output voltage from said bridge, a second filter network connected between the control grid and cathode of said second vacuum tube means, said second filter also comprising a pair of serially connected capacitors connected in parallel with a first resistance, one end of said last mentioned first resistance being connected to the control grid of said second vacuum tube means, the other end being connected to the cathode of said first vacuum tube means, a second resistance having one end connected to the junction of the serially connected capacitors of said second filter network, the other end being connected to the cathode of said second vacuum tube means, said second filter network being adapted to reject a component alternating current ripple appearing on the output voltage from the cathode of said first vacuum tube means, a third vacuum tube means having at least a plate, a cathode and a control grid, an anti-hunting means, said means comprising a filter network between the control grid and cathode of said third vacuum tube means, said filter network being similar in arrangement to said first filter network and said second filter network and comprising a pair of serially connected capacitors in parallel with a first resistance, one end of said first resistance being connected to the cathode of said second vacuum tube means the other end being connected to the control grid of said third vacuum tube means, a second resistance having one end connected to the junction of the last mentioned serially connected capacitors, the other end being connected to the cathode of said third vacuum tube means, said anti-hunting means being adapted to reject the frequency at which said regulator would tend to hunt, a connection from the plate of said third vacuum tube means to

the direct current portion of said saturable core reactor whereby the impedance of said alternating current portion is varied in accordance with the plate current through said direct current portion to thereby maintain the voltage of said output within said predetermined limits.

12. A highly accurate electronic voltage regulator adapted to regulate the magnitude of an alternating current voltage between predetermined limits, said regulator including an input circuit having the primary of an auto-transformer connected thereto, an output circuit associated with the secondary of said auto-transformer, a saturable core reactor having an alternating current portion and a direct current portion, means for altering the voltage across said output circuit by varying the impedance of said alternating current portion, a bridge circuit having a diode vacuum tube forming one of the arms thereof, the filament of said diode being connected across said output circuit whereby a variation in the output voltage varies the temperature of said filament to unbalance said bridge and vary the output thereof, an amplifier connected with the output of said bridge, a second vacuum tube having at least a plate, a cathode and a control grid, means for applying the output of said amplifier to said control grid, a first transformer forming a portion of a power supply adapted to supply direct current voltage to said second vacuum tube, a second transformer forming a portion of a power supply adapted to supply direct current voltage to said bridge circuit, one side of the primary winding of each of said transformers being connected to one lead of said output circuit, the plate of said second vacuum tube being connected through the direct current portion of said saturable core reactor to the power supply of said first transformer, the other side of each of said primaries being connected by said diode vacuum tube whereby on said diode vacuum tube being removed from said bridge the said primaries are deenergized and the voltage across said output circuit is decreased.

13. A highly accurate electronic voltage regulator adapted to regulate the magnitude of an alternating current voltage between predeter-

mined limits, said regulator including an input circuit, transformer means having a first portion associated with said input circuit, an output circuit connected with a second portion of said transformer means, a saturable core reactor having an alternating current portion and a direct current portion, means for altering the voltage across said transformer means and thereby the output circuit by varying the impedance of said alternating current portion, a bridge circuit having a diode vacuum tube forming one of the arms thereof the filament of said diode being connected across said output circuit whereby a variation in the output voltage varies the temperature of said filament to thereby unbalance said bridge, a plurality of variable resistors, switch means for selectively connecting said resistors in the filament circuit of said diode whereby the filament current may be varied to adapt the circuit for operation over a wide range of desired output voltages, a direct current amplifier, filter means associated with said direct current amplifier, means for applying the output of said bridge circuit through said filter means to said direct current amplifier whereby said filter means is adapted to reject unwanted alternating current ripple which may be present in the output from said bridge circuit, vacuum tube means, means for applying the output from said direct current amplifier to said vacuum tube means to control the plate current thereof, and means for applying said plate current to the direct current portion of said saturable core reactor to control the impedance of said alternating current portion and to thereby maintain the voltage of said output circuit within said predetermined limits.
